UNITED STATES PATENT OFFICE

BRUCE W. GONSER, OF AMARILLO, TEXAS, ASSIGNOR TO AMERICAN SMELTING AND REFINING COMPANY, OF NEW YORK, N. Y., A CORPORATION OF NEW JERSEY

APPARATUS FOR RECOVERING FURNACE VENTILATOR FUME

Application filed August 8, 1929. Serial No. 384,344.

This invention relates to the smelting of zinc, and more particularly to a method and apparatus for recovering volatilized metals which would otherwise escape from a retort 5 zinc furnace, and treating the recovered material for reclaiming the metal content thereof.

The invention applies particularly to a type of retort zinc furnace in which certain volatilized metals escape condensation and are lost at the front of the furnace. This uncondensed material consisting largely of oxides of zinc, lead and cadmium escapes from openings in the front end and at the 15 base of the condenser and passes by the aid of natural draft through ventilator openings in the roof of the building covering a block of the furnaces.

The present invention provides for intercepting and catching the escaping fume whereby the metal value contained therein may be recovered, and the nuisance caused by the smoke or fume is largely eliminated. For this purpose a hood is fitted over the 25 front end and at the top of the furnace in such manner as to intercept the natural flow of fume laden gases. The fume is removed from the hood by a suitable fan and is applied to a baghouse, Cottrell precipitator or 30 other gas filtering medium in which it is recovered. The fume is then introduced into the plant flow of materials at a point where the metals contained therein can be recovered.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its 45 operation and the manner of its organization may be better understood by referring to the following description taken in connection with the accompanying drawings forming a part thereof, in which

Fig. 1 is a front elevation of a bank of

zinc retorts showing the hood in position; and

Fig. 2 is a section taken on the line 2—2 of Fig. 1.

Like reference characters denote like parts 55 in the several figures of the drawings.

In the following description and in the claims parts will be identified by specific names for convenience, but they are intended to be as generic in their application to similar 60 parts as the art will permit.

Referring to the drawings more in detail, the invention is shown as applied to a bank of retorts 1 positioned within the furnace 2 and provided with condensers 3 which extend 65 forwardly of the furnace and are utilized for controlling the operation of the retorts in a manner well known in the art. A hood 5 is placed above and in front of the furnace 2 in a position to catch the fume rising from 70 condensers 3. Hood 5 is provided with a plurality of valves 6 by means of which the natural draft from the hood may be controlled, and a plurality of stationary baffles 7. Handles 4 are secured to valves 6 and extend 75 outside of hood 5 where they are accessible for control purposes. Handles 4 may be operated by any suitable means such as a cord (not shown). The ends of hood 5 are formed with slots 8 to permit the operating shield of 80 the furnace to be used without interference.

Hinged extensions 9 are hung from the lower part of hood 5 and extend downwardly a predetermined distance in front of the furnace to insure that the fume from condensers 85 3 enters hood 5. Extension 9 may extend downwardly any convenient distance and is hinged to afford access to the retorts for operating purposes. Hood 5 terminates in duct 10 by means of which the fume is drawn to 90 a suitable recovering apparatus (not shown) such as a baghouse, Cottrell precipitator or other gas filtering medium.

It is to be noted that the hood is so placed 95 as to catch the fume laden gases as they issue from the condensers and travel upwardly, yet is in a position where it will not interfere with the normal operation of the furnace. It must extend a sufficient distance from the front of the furnace to permit the shields normally 100

used in charging and discharging the retorts and drawing metal to pass without interference, but no further than is necessary to intercept the gas stream issuing from the condensers. The hood is so positioned as to effectively catch the fume laden gases and at the same time prevent the entrance of an excess of outside air. The hinged extension 9 further assists in preventing an excessive amount of outside air from entering the hood and subsequently being drawn to the recovery apparatus. Valves 6 assist in securing the proper local draft control particularly when drawing metal and discharging the retorts.

15 Gas is withdrawn from the hood at such a rate as to approximately equalize the pressure caused by the natural draft up the face of the furnace. In this manner a minimum of outside air is drawn into the hood, yet practically all of the fume evolved is entrapped. In actual practice 85% of the fume has been recovered from the condensers without handling more than 75,000 cubic feet of gas per minute at 125° F. per block of 800 retorts.

20 The dust recovered in the baghouse is preferably charged along with other zinciferous materials to a sintering machine together with the usual charge which is being prepared for retort smelting. The dust thus becomes incorporated in the sinter and is rendered suitable for smelting in the retort. The sinter is then crushed or broken in the usual manner and is charged to the retort in which the metal values are recovered. The process is accordingly cyclic in that the fume escaping from the retort is caught and again rendered suitable for application to the retort.

25 The addition of ventilator fume to the regular sintering machine charge has been found to assist in the operation inasmuch as the fume operates as a diluent to lower the sulphur content of the charge. The percentage of fume recovered varies widely in practice and is dependent largely on the operating conditions of the retort. In the drawings the hood has been shown as applied to a Belgian retort furnace, although it is to be understood that the invention may be applied to various other types of zinc furnaces as desired.

30 While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

35 What is claimed is:

1. In combination with a bank of zinc retort furnaces a hood positioned above and in front of said furnaces and extending throughout the length of said bank, said hood being provided with a plurality of horizontally spaced valves for selectively controlling

the draft to the various furnaces and terminating in a horizontal duct by means of which the fume is withdrawn, stationary baffles being mounted in said hood between said valves for further controlling the flow of gases. 70

2. In combination with a bank of zinc retort furnaces having an operating shield, a hood positioned above and in front of said furnaces and extending throughout the length of said bank, said hood being provided with a plurality of horizontally spaced valves for selectively controlling the draft to the various furnaces and terminating in a horizontal duct by means of which the fume is withdrawn, the ends of said hood extending below said shield and being recessed to permit passage of said shield without interference. 75

3. In combination with a bank of zinc retort furnaces, a hood positioned above and in front of said furnaces and extending throughout the length of said bank, said hood being provided with a plurality of horizontally spaced valves for selectively controlling the draft to the various furnaces and terminating in a horizontal duct by means of which the fume is withdrawn, and a downwardly extending extension hingedly secured to said hood and adapted to hang in front of said retorts for further controlling the flow of fume. 80

4. In combination with a bank of zinc retort furnaces, a hood positioned above and in front of said furnaces and extending throughout the length of said bank, a horizontal duct communicating with said hood for withdrawing fume therefrom, said hood having a plurality of horizontally spaced valves located therein for variably controlling the draft longitudinally thereof. 100

105 In testimony whereof I have hereunto set my hand.

BRUCE W. GONSER.
